(57) **CLAIM**

The ornamental design for a deformable fastener for photovoltaic devices, as shown.

DESCRIPTION

FIG. 1 is a top perspective view of a deformable fastener for photovoltaic devices in accordance with the present design. FIG. 2 is a left side elevational view of the deformable fastener of FIG. 1.

FIG. 3 is a right side elevational view of the deformable fastener of FIG. 1.

FIG. 4 is a front edge elevational view of the deformable fastener of FIG. 1.

FIG. 5 is a back edge elevational view of the deformable fastener of FIG. 1.

FIG. 6 is a top plan view of the deformable fastener of FIG. 1; and,

FIG. 7 is a bottom plan view of the deformable fastener of FIG. 1.
